CLAIM

The ornamental design for a cable cutter, substantially as shown.

DESCRIPTION

FIG. 1 is a plan view of a cable cutter showing our new design;

FIG. 2 is a side elevational view;

FIG. 3 is an end view;

FIG. 4 is another end view;

FIG. 5 is a cross-sectional view taken on line 5—5 of FIG. 1; and

FIG. 6 is a plan view; similar to FIG. 1, but showing the cutter in an open position.
